UNITED STATES PATENT OFFICE

2,035,271

GAME APPARATUS

Bon MacDougall, Los Angeles, Calif., assignor to
Fred C. McClellan, Chicago, Ill.

Original application June 28, 1934, Serial No.
732,754. Patent No. 1,973,820, dated September
18, 1934. Divided and this application July 14,
1934, Serial No. 735,106

3 Claims. (Cl. 273—121)

This invention relates to certain novel improvements in a game apparatus and particularly has reference to an arrangement wherein playing balls may be progressively advanced 5 from one point to another upon a playing surface and has for its principal object the provision of an improved structure of this character which will be highly efficient in use and economical in manufacture.

10 The present invention is a division of that described and shown in my Patent No. 1,973,820 filed June 28, 1934, for Coin controlled game apparatus.

In one preferred form, the present invention 15 contemplates the utilization of ball controlled means for progressively advancing a ball around a baseball diamond arranged upon a playing surface.

With the foregoing and other objects in view 20 the ball progressing means preferably comprises an electromagnetic circuit including a ball-advancing member in the form of a solenoid, the said circuit being closed by a ball traveling along a ball return runway from the playing surface 25 to the elevating means, or to a point adjacent the latter.

Other objects will appear hereinafter.

The invention consists in the novel combination and arrangement of parts to be hereinafter 30 described and claimed.

The invention will be best understood by reference to the accompanying drawing, showing the preferred form of construction and in which:

Fig. 1 is a fragmentary perspective view of a 35 preferred form of the invention;

Fig. 2 is a vertical sectional detail view of the same taken substantially on line 2—2 of Fig. 1; and

Fig. 3 is a fragmentary vertical sectional detail view of the same taken substantially on line 3—3 of Fig. 2.

The game apparatus shown and described in my co-pending application hereinbefore referred to, and as shown and described fragmentarily in the drawing of this, the present application, comprises an inclined playing board 10 onto the upper portion of which balls are propelled one at a time (by means not shown) so as to gravitate 45 thereover toward the lower end thereof. Provided upon this play board 10 is an object 11 which, in the form of the invention shown simulates the diamond of a baseball field. This diamond is defined by side rails 12 which are supported from the play board 10 by means of posts

13 which are arranged at the corners of the diamond.

While I have shown a fragment of a baseball diamond upon the playing board 10 it is obvious that the object 11 need not necessarily represent 5 or simulate a baseball diamond as the present invention, which will now be more fully described, may be utilized for progressively advancing a ball along runways or guideways of various forms and designs arranged upon a playing surface. 10

Between the rails 12 there are formed in the play board 10 grooves or runways 14 which guide the balls and are substantially parallel to the rails 12.

Each corner 15 of the diamond is intended to 15 represent or simulate a base and at each corner there is formed in the play board 10 an opening 32. Arranged in each of these openings 32 is a ball-receiving seat or cup 33. These ball seats or cups 33 are hinged to the play board 10 in a manner shown and described in my above-identified patent and are normally held in raised position by means of a sliding panel 34 which is arranged below the play board 10. However, when the sliding panel is moved by the player, at the end 20 of a game, to discharge the played balls from the playing surface for return to the elevating device (not shown) the ball seats or cups 33 drop by gravity to discharge any balls held thereby 25 for return to the elevating means. 30

Formed in each ball seat or cup 33 is a slot 16 and projecting upwardly through each of these slots 16 is a finger 17, each of these fingers 17 being formed as an integral part of a ball-advancing member or solenoid actuated slide bar 35 18. Each finger 17 is normally held at one end of the corresponding slot 16 by means of a resetting spring 21, one end of the spring 21 being secured to the ball-advancing member or arm 18 of the solenoid, as at 22; and the other end of 40 the spring 21 being connected to an inclined floor 23 which is disposed beneath the play board 10.

The solenoid 19 is connected, in an electromagnetic circuit, with a suitable source of electric energy 24, by means of suitable conductor wires 45 25, and arranged in this circuit are suitable switch structures 26 which may be of any approved design. Each of these switch structures 26 in the present instance includes a movable contact member or contact gate 27 and each of 50 these movable contact members or gates 27 is adapted to have contact under certain conditions with a relatively stationary contact member or post 28 to complete the circuit between the solenoid 19 and the source of electric energy 25. 55

These contact members or gates 27 are pivotally mounted upon posts 29 which project upwardly from the sub-floor 23 and are normally held, in the position illustrated in Fig. 1, by means of 5 springs 30, so as to be successively engaged by balls traveling along the runways 31 from the playing board 10 to a point adjacent the elevating means.

Arranged around each ball seat or cup 33 is a 10 circular wire ball retaining ring or hoop 35.

The operation of the apparatus is as follows:

When a ball enters one of the inclined return runways 31 from the play board 10 it travels by gravity down the runway 31 and successively engages the movable contact members or contact gates 27 and as it engages these movable contact members or gates 27 it pivots them against the action of their resetting springs 30 into contact with the corresponding stationary contacts 20 28, thereby closing the electromagnetic circuit (Fig. 2) and energizing the solenoid 19. Upon energization of the solenoid 19 the ball-advancing member 18 and finger 17 are quickly moved in the slot 16 of the ball seat or cup 33, against the action of the resetting spring 21, and thereby propel the ball with which the finger 17 contacts, from the said ball seat 33, over the wire retaining ring 35, and along the groove or channel 14 to the next succeeding corner of the diamond or to the next station or post arranged in the guideway or track grooves 14 if the grooves 30 14 are arranged in some other pattern or design than as a baseball diamond.

It is apparent that the structure hereinbefore described and shown is capable of universal application in connection with amusement games wherein a ball or balls are projected upon a playing surface for movement thereover and the invention is not limited to the specific form and 40 design shown.

While I have illustrated and described the preferred form of construction for carrying my invention into effect, this is capable of variation and modification, without departing from the 45 spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a game apparatus, the combination of: 55 A member providing a playing surface; a guideway or track on said playing surface for guiding a ball thereover; an annular ball seat arranged in said guideway or track; said ball seat having a slot or opening formed therein; an inclined ball return runway below said playing surface and having communication therewith; means for progressively advancing a ball along said guideway or track from point to point thereon; said means comprising an electromagnetic circuit including an electromagnetically operated ball advancing member having a portion mov-

able in said slot and arranged in the path of movement of a ball traveling along said guideway or track; and means arranged in said runway and engageable by balls traveling therealong to close said circuit and operate said ball advancing member so as to move the said portion thereof in said slot and propel a ball off from said ball seat along said guideway or track. 5

2. In a game apparatus: A cabinet including a member providing a play surface; a ball runway or track on said playing surface for guiding a ball thereover; said member having an opening formed therein; the said opening being arranged in said ball runway or track; an annular cup or ball seat disposed in the said opening; said cup or ball seat being hingedly mounted upon said member and having a slot formed therein; a ball return runway below said playing surface and having communication therewith; means for moving a ball off from said ball seat or cup along said first-named runway or track including an electromagnetically operated ball-advancing member having an upwardly extending portion movable in said slot; means arranged in said ball return runway and engageable by balls traveling thereby to close said circuit and operate said ball-advancing member so as to move the said portion thereof in said slot and project a ball off from said ball seat along said first-named runway or track; and a member slidably mounted in said cabinet below said playing surface for retaining said ball seat or cup in raised position against the action of gravity. 20 25 30

3. In a game apparatus: A cabinet including a member providing a playing surface; a ball runway or track on said playing surface for guiding a ball thereover; said member having an opening formed therein; the said opening being arranged in said ball runway or track; an annular cup or ball seat disposed in the said opening; said cup or ball seat being hingedly mounted upon said member and having a slot formed therein; a ball return runway below said playing surface and having communication therewith; means for moving a ball off from said ball seat or cup along said first-named runway or track including an electromagnetically operated ball-advancing member having an upwardly extending portion movable in said slot; means arranged in said ball return runway and engageable by balls traveling thereby to close said circuit and operate said ball-advancing member so as to move the said portion thereof in said slot and project a ball off from said ball seat along said first-named runway or track; a member slidably mounted in said cabinet below said playing surface for retaining said ball seat or cup in raised position against the action of gravity; and a flexible wire retaining ring arranged around the said ball seat or cup and over which a ball may be projected, by the said upwardly extending portion of the said ball-advancing member, from the said ball seat into the said runway. 40 45 50 55 60 65
